UNITED STATES PATENT OFFICE.

MARTIN ROSS, OF BUFFALO, NEW YORK, ASSIGNOR TO THE PECK, STOW & WILCOX COMPANY, OF SOUTHBURG, CONNECTICUT.

DESIGN FOR A TURNING-MACHINE ROLLER.

SPECIFICATION forming part of Design No. 25,779, dated July 14, 1896.

Application filed May 28, 1896. Serial No. 593,511. Term of patent 14 years.

To all whom it may concern:

Be it known that I, MARTIN ROSS, a citizen of the United States, residing at Buffalo, in the county of Erie and State of New York, have invented and produced a new and original Design for a Turning-Machine Roller, of which the following is a specification, reference being had to the accompanying drawings, in which—

Figure 1 is a front elevation of a turning-machine roller, showing my design. Fig. 2 is a side elevation thereof.

My roller comprises a short cylinder with a V-shaped groove near one side thereof.

A designates the roller, which is mainly in the form of a short cylinder, but which is provided near its outer side or end with a V-shaped groove 3, slightly truncated at the bottom 4. The location of said groove is such as to leave a narrow band 5 in the original cylindrical surface of the roller, as shown.

What I claim is—

The design for a turning-machine roller substantially as shown and described.

MARTIN ROSS.
